UNITED STATES PATENT OFFICE.

WILLIAM S. CARTER, OF PEORIA, ILLINOIS, ASSIGNOR TO BROTHERHOOD OF LOCOMOTIVE FIREMEN AND ENGINEMEN, OF PEORIA, ILLINOIS, (A MUTUAL BENEFIT ASSOCIATION.)

DESIGN FOR A BADGE.

No. 38,445.

Specification for Design.

Patented Feb. 19, 1907.

Application filed January 2, 1907. Serial No. 350,536. Term of patent 14 years.

To all whom it may concern:

Be it known that I, WILLIAM S. CARTER, a citizen of the United States, residing at Peoria, in the county of Peoria and State of Illinois, have invented a new, original, and ornamental Design for a Badge, of which the following is a specification, reference being had to the accompanying drawing, forming part thereof.

The figure is a plan view of a badge, showing my new design.

I claim—

The ornamental design for a badge, as shown.

WILLIAM S. CARTER.
